(57) **CLAIM**

The ornamental design for a meeting timer, as shown and described.

DESCRIPTION

FIG. 1 is a front perspective view showing my new design;

FIG. 2 is a front elevation thereof;

FIG. 3 is a rear elevation thereof;

FIG. 4 is a left end view thereof;

FIG. 5 is a right end view thereof;

FIG. 6 is a top view thereof;

FIG. 7 is a bottom plan view thereof; and,

FIG. 8 is an enlarged view of the screen of FIGS. 1, 2 and 6. The screen is shown separately in FIG. 8 for ease of illustration.

The broken lines in the Figures are for illustrative purposes only and form no part of the claimed design.
